LABEL CARRYING CONTAINER

George D. Hofe, South Orange, N. J.

Application February 27, 1934, Serial No. 713,087

8 Claims. (Cl. 40—7)

My invention relates to label-carrying containers and refers particularly to containers carrying designating labels affixed thereto by means of the container closure.

Manufacturers frequently market a variety of commodities in containers of the same size and shape, as for instance products such as face cream, face cosmetics, face rouge, lip rouge, liquid preparations for the treatment of the hair, lotions, et cetera.

The designation of the particular ingredient in the container is accomplished by embossing, or stamping, the indicating words upon the container closure, or by pasting a printed label thereon.

Further it is frequently desirable to incorporate with the container, printed information regarding the properties of the material, its method of use and such other information as is desirable, and this is usually accomplished by placing such printed material within a box, or carton, carrying the commodity container.

The embossing of the designating names of a plurality of products, each upon a limited number of containers, when all of the containers are of uniform size and shape represents a very considerable expense.

It is evident that the purchase of a large number of similar containers free from designating embossings will cost much less per unit, than the purchase of the same number of containers, divided into a number of groups, each group having a different embossing thereon.

It is further evident that the necessity of employing a box or carton, for each container in order that the printed material may not become separated therefrom during shipment and handling is of considerable expense; and it is still further evident, that a label pasted upon the container, will not overcome this expenditure for boxes or cartons.

My invention overcomes all of the above, and other, objectionable features incident to the above described methods of packaging and marking containers, and presents a means whereby containers for a plurality of commodities may be purchased in bulk without the necessity of embossing, whereby the printed matter may be incorporated with each container without the expense of boxes and cartons and whereby the expense of pasting labels upon the containers may be avoided.

In a broad way my invention consists of a label of paper, or other suitable material, the central portion of which is of such size and

shape as to have printed thereon such designating marks and information as may be desired, the two extremity portions of the labels being of such size and length as to allow them to be passed downwardly over the outer face of the side of a container closure and upwardly across the inner face thereof. When such closure having my label positioned thereon as described is placed upon the neck of a container, the label will be firmly held in position across the outer face of the closure.

If desired, printed material carrying such information as may be necessary, can be affixed to the under side of the central portion of my label, in folded form if desired, and hence is carried by the container until the closure is removed, when it is readily available for use.

It will thus be noted that my invention allows of the purchase of containers in large quantities even when they are to be employed for a number of products, saves the expense of pasting labels and obviates the necessity of boxes and cartons when it is desirable to have printed matter accompanying the containers.

In the accompanying drawing illustrating modified forms of the device of my invention, similar parts are designated by similar numerals.

Figure 1 is a perspective view of one form of the container and label of my invention.

Figure 2 is a bottom view of the device of Figure 1.

Figure 3 is a top view of the closure member and label in position for attachment to a container.

Figure 4 is an enlarged section through the line 4—4 of Figure 1.

Figure 5 is a perspective view of the label and partially unfolded directions element.

Figure 6 is a side view of the label and unfolded direction element removed from the closure member.

Figure 7 is a broken vertical section of a modified form of my device, in which the closure is maintained in place by frictional contact with the neck of the container.

The particular form of my device shown in Figures 1 to 6 consists of an annular cover, or closure member, having the top 10 and the dependent side 11, the inner face of the side 11 being threaded as shown.

A strip label 12, composed of paper, cardboard, fabric, leather, cellophane or other suitable pliable material, has an annular central portion 13, the length of the strip 12 being such that it can be bent over the side 11 and continued

across the threaded portion of the inner face thereof.

A folded piece of suitable material 14 is attached to the central portion of the inner face 5 of the strip 11, which folded member 14 is adapted to have printed thereon directions for the employment of the contents of the container or other desired information.

An annular container consisting of the bottom 10 member 15 and the side member 16, has the upper outer portion of said side threaded to mesh with the threads of the closure member side 11.

If desired the strip label 12 may be scored at 15 the lines of its curvature, as at 17, 17, 17.

In applying the device of my invention, the label is placed upon the top 10 of the closure member, and bent down and around the side 11 of the closure member, the strip extending across 20 the threads in said closure member. With the label in this position, the closure member is placed upon the container and around the upper portion of the side 16, and screwed thereon. It will thus be seen that the label is firmly attached in position across the upper outer face 25 of the closure member while said closure member is screwed upon the container.

In order that the contents 18 of the container 30 may be identified when the label is removed and perhaps destroyed or lost, I prefer to paste or otherwise attach an identifying label 19 upon the bottom 15 of the container.

The modification of my device shown in Figure 7 is similar to that previously described, except that the neck of the container and the side 35 of the closure are not threaded, the closure being maintained in place by frictional contact.

In the particularly described forms of my invention, I have shown an annular jar, but it is 40 evident that my invention is much broader than the particular illustrations, and that the container may be a bottle or of other form and that it may be square, oval or of other configuration, as long as the neck thereof will allow 45 of the attachment of a closure and therefore I do not limit myself to the particular described form, shape, size or material of container, container closure, or labels as these have been given simply as a means for clearly describing my invention.

50 What I claim is:—

1. In a label-carrying container, in combination, a container having a neck, a closure having a downwardly extended side capable of being placed upon said neck and a label positioned 55 across the outer face of said closure and extending between the inner face of said closure side and the outer face of said container neck, said label being capable of removal intact upon the removal of said closure from said neck.

2. In a label-carrying container, in combination, a container having a neck, a closure having a downwardly extended side capable of being placed upon said neck and a label main- 60

tained in fixed position across the outer face of said closure by the inner face of said closure side and the outer face of said container neck, said label being capable of removal intact upon the removal of said closure from said neck. 5

3. In a label-carrying container, in combination, a container having a neck, a closure having a downwardly extended side capable of being placed upon said neck, a label positioned across the outer face of said closure and extending between the inner face of said closure side and the outer face of said container neck, said label being capable of removal intact upon the removal of said closure from said neck, and a sheet of material attached to at least a portion of the under face of said label. 10 15

4. In a label-carrying container, in combination, a container having a neck, a closure having a downwardly extended side capable of being placed upon said neck and a label maintained 20 in fixed position across the outer face of said closure by the inner face of said closure side and the outer face of said container neck, said label being capable of removal intact upon the removal of said closure from said neck, and a sheet 25 of material attached to at least a portion of the under face of said label.

5. In a label-carrying container, in combination, a container having an externally threaded neck, a closure capable of being threaded upon 30 said neck and a label positioned across the outer face of said closure and extending between the threaded portions of said neck and said closure, said label being capable of removal intact upon the removal of said closure from the container. 35

6. In a label-carrying container, in combination, a container having an externally threaded neck, a closure capable of being threaded upon 40 said neck and a label maintained in fixed position across the outer face of said closure by the threaded portions of said closure and said neck, said label being capable of removal intact upon the removal of said closure from said container.

7. In a label-carrying container, in combination, a container having an externally threaded 45 neck, a closure capable of being threaded upon said neck and a label positioned across the outer face of said closure and extending between the threaded portions of said neck and said closure, said label being capable of removal intact upon 50 the removal of said closure from the container, and a sheet of material attached to at least a portion of the under face of said label.

8. In a label-carrying container, in combination, a container having an externally threaded 55 neck, a closure capable of being threaded upon said neck, a label maintained in fixed position across the outer face of said closure by the threaded portions of said closure and said neck, said label being capable of removal intact upon 60 the removal of said closure from said container, and a sheet of material attached to at least a portion of the under face of said label.

GEORGE D. HOFE.
